Specification of Letters Patent.

Patented May 7, 1918.

Application filed March 20, 1916. Serial No. 85,363.

To all whom it may concern:

Be it known that I, WILLIAM H. SOMMER, a citizen of the United States, residing at Peoria, in the county of Peoria and State 5 of Illinois, have invented new and useful Improvements in Clamps, of which the following is a specification.

This invention has reference to clamps, and relates particularly to that form of 10 clamp used on wire fence machines and usually disposed between the wire connecting mechanisms and the reel or wrapper of the machine, said clamp having means to grip the strand wires of the fence fabric and to 15 crimp the same.

The invention has for its object to improve the crimping mechanism on the clamp and to provide a new and improved means for actuating said crimping mechanism, said 20 actuating means being of few parts, simple in construction and having a timed relation relative to the other working parts of the machine to insure the proper gripping, crimping and releasing of the strand wires 25 during their movement from the wire connecting mechanisms to the reel or wrapper of the fence machine.

That the invention may be more fully understood, reference is had to the accompanying drawings, in which,

Figure 1 is a vertical longitudinal sectional view of the clamp;

Fig. 2 is a vertical cross section of the clamp as the same would appear if taken 35 on the line 2—2 of Fig. 1, and shows in addition a guiding roller for the strand wires and a butterfly wheel for guiding the strand wires from the clamp to the reel or wrapper;

Fig. 3 is an end view partially in section 40 showing parts of the clamp in dotted lines and the position of certain of the rollers which operate upon the crimping bars of the clamp;

Fig. 4 is an end view similar to Fig. 3 45 but of the opposite end of the clamp, the same being shown in dotted lines, and in addition a roller and its position is illustrated which acts upon the crimping bars to return them to a position to receive the 50 strand wires of the fence fabric.

Fig. 5 is a perspective view of a part of

one end of the clamp showing the locking means for holding the crimping bars in clamping position on the strand wires;

Fig. 6 is a perspective view showing how 55 the crimping bars grip and crimp a strand wire;

Fig. 7 is a perspective view showing the locking parts for holding the crimping bars 60 in locking position;

Fig. 8 is a detail perspective view showing a steel hardened pin in one of the crimping bars; and

Fig. 9 is a plan view partially in section 65 of the roller and the support shown in Fig. 4.

Like characters of reference denote corresponding parts throughout the figures.

The clamp may be of any suitable diameter and also of any suitable length, and includes a driving shaft 10 on which are mounted in spaced relation the heads 11, which support the gripping and crimping bars for the strand wires, and guiding bars to present an annular surface on which the 75 wires may be directed around the clamp. By reference to Fig. 2 it will be observed that there are a plurality of gripping and crimping mechanisms suitably spaced around the clamp on the heads 11, and the description of one set of gripping and crimping devices will suffice for all, as they are all duplicates of each other and operate and are actuated in the same manner.

12, 12 and 13 designate gripping and 85 clamping bars which extend longitudinally of the clamp and are mounted upon the heads 11, bars 12, 12 being fixedly secured to the heads 11, and between said bars 12 is disposed the bar 13 which is movable longitudinally of the clamp between said bars and retained in operative relation therewith by the straps 14 secured to the bars 12. One end of the bar 13 is rounded for a portion of its depth as at 15 and has the squared 90 shoulder portion 16, for purposes which will be more fully explained, and the opposite end of said bar 13 is rounded its full depth as at 17, for purposes which will be more fully explained. The bar 13 at that end 95 100 which is provided with the rounded and squared shoulder portion, as explained, is

provided with a cut-out portion 18, and operating in said cut-out portion is a pawl 19 carried upon a stem 20, the opposite ends of the stem passing through openings 21 in the bars 12 to provide a pivotal support for the pawl 19 on the bars 12 within the cut-out portion 18, as best seen in Figs. 1, 5 and 7. The outer end of the pawl is formed with a tooth 22 having the squared or flat engaging face 23 adapted to ride over and engage or bear against the squared shoulder portion 16 on the end of the bar 13. This engagement between the end of the pawl 19 and the end of the bar 13 will take place immediately after the engagement of the strand wires by the bar 13, in a manner to be more fully explained, and which will be released therefrom at a proper time in the rotation of the clamp, and when it is desired to release the strand wires from the clamp.

At predetermined points, either at uniform or graduated distances from each other, the bar 13 is cut out and formed with recessed or slotted portions 24, providing the spaced walls 25 and 26, between which and into said recesses or slots strand wires will seat themselves during the rotation of the clamp. As the strand wires will be operated upon by the wall portions 26 of said slots or recesses 24, steel hardened pins 27 which are replaceable are set in said walls to receive the wear and form a bearing surface for the strand wires. The bars 12, at points which coincide with the recesses or slots 24 in the bar 13, are also provided with recessed or slotted portions 28, providing the spaced walls 29 and 30, between which and into said recesses or slots 28 the strand wires will seat themselves during the rotation of the clamp, and as the strand wires will be operated upon by the walls 29 of the slots 28 in the bars 12, and in coöperation with the wall 26 of the bar 13, steel hardened pins 31 which are replaceable are set in said walls to receive the wear and form a bearing surface for the strand wires. The steel hardened pins 27 and 31 have beveled ends 32 to facilitate the easy entrance and removal of the strand wires between said pins 27 and 31, it being observed by reference to Fig. 6 that the pins of the bars 13 and the pins of the bars 12 are placed in the opposite walls so as to form a gripping means upon each side of the strand wires, and as will be explained, the steel hardened pins 27 in the bar 13, will be moved toward the pins 31 for the purpose of gripping the strand wires between said pins and to crimp the wires therebetween, as shown in Fig. 6.

Extending longitudinally of the clamp and secured to the heads 11 in juxtaposition to the bars 12 are other bars 33 which constitute a part of the frame-work of the clamp and serve to retain the bars 12 in fixed position, and said bars 33 where the strand

wires ride over the same to enter the recesses or slots in the bars 12 and 13, are formed with recesses 34 in their outer surface to present a rounded surface on the clamp for the strand wires, and to prevent any sharp edges or corners against which the strand wires might bear. Also extending longitudinally of the clamp and disposed in proper spaced relation between each set or series of gripping and clamping bars 12 and 13, are provided other bars 35 which form a part of the framework of the clamp and produce a surface over which the strand wires will travel, as shown in Fig. 2. The bars 12, 13 and 33 are seated in recesses or cut-out portions 36 in the heads 11, and the bars 35 are seated in slotted or recessed portions 37 in said heads 11, see Fig. 5.

At one end of the clamp in diametrically opposed positions to each other, and in a vertical plane extending through the axis of the shaft 10, are rollers 38 and 39, each being journaled on vertically disposed stub shafts 40 having a bearing in a frame part 41. These rollers 38 and 39 are located at that end of the clamp at which the pawls 19 are located which are adapted to engage with the bars 13, and said roller 38 is adapted to ride against the rounded portion 15 of the bar 13 to move said bars longitudinally of the clamp to cause the same in conjunction with the bars 12 to grip the strand wires as shown in Fig. 6, and such movement of the bar 13 will permit the tooth 22 of the pawl 19 to drop over the end of the squared shoulder portion 16 on the bar 13, which will lock the bar 13 in the operative position shown in Fig. 6. During the further and continued rotation of the clamp and when each bar 13 comes into alinement with the roller 39, this roller will engage with the rounded surface 15 of the bar 13 and impart a further slight longitudinal movement of said bar, which will permit the pawl 19 to release itself from the end of the bar 13, as shown in Fig. 1, so that immediately thereafter and during the further and continued rotation of the clamp, the roller 42 which is yieldingly held in operative position by means of a spring 43, will bear against the rounded portion 17 on the opposite end of each of the bars 13 and move said bars in an opposite direction longitudinally of the clamp, or in a retracted position from that in which the bar 13 is shown in Fig. 6, so that as the clamp moves into a position for the strand wires to enter the slots or recesses 24 and 28 in the bars 13 and 12, said wires may enter the same without being impeded or retarded, in which position the bars 13 may be acted upon by the roller 38 to clamp the strand wires, as shown in Fig. 6, and said bars 13 retained in their inward positions through the engagement of the pawls 19 with the ends of the bars 13,

as shown in Fig. 1. The roller 42 is journaled on the outer end of a bar 44, to which said bar one end of the spring 43 is secured, its opposite end being secured to a frame 5 part of the machine. The opposite end of the bar 44 is angular in shape and is secured to a frame part of the machine by the yielding connecting bolts 45, see Figs. 4 and 9. The spring 43 is provided to hold the 10 bar 44 with the roller 42 in an operative position to engage with the rounded end portion 17 of the bars 13, and the yielding connection 45 for the bar 44 with the frame is such that said bar may give when engagement 15 takes place between the roller 42 and any of the bars 13 without any possibility of breakage of such operative parts.

The shaft 10 of the clamp is provided with a gear wheel 46 and such gear wheel 20 may be driven by gearing from any part of the fence machine on which the clamp is mounted. To guide the strand wires to the clamp and in a position to enter the slots or recesses 24 and 28 in the bars 13 and 12 respectively, I provide the roller 47, see Fig. 2, and in said figure I also show a butterfly wheel 48 to guide the strand wires as they leave the clamp, and to retain the same in operative position on the clamp and until 25 they are released to be directed to the reel or wrapper, not shown.

In operation, the strand wires leaving the wire connecting mechanisms, with the stay wires attached thereto, may be drawn out 30 by any pull-out mechanism from which the finished fabric is fed over the clamp, the strand wires passing under the guiding roller 47 and into the slots or recesses 24 and 28 in the bars 13 and 12 respectively, 35 as they come into position to receive the strand wires during the continued rotation of the clamp. The bars 13 having been moved to inoperative position by the roller 42 bearing against the rounded end 17 of 40 said bars 13, permitting the strand wires to enter into the slots or recesses 24 and 28, the bars 13 will be moved to gripping position to crimp the strand wires as shown in Fig. 6, by the engagement of the roller 38 with 45 the rounded ends 15 of said bars 13, which movement of the bars 13 will permit the pawls 19 to drop over the ends of the bars 13 by gravity and lock the same in the crimping position shown in Fig. 6. When 50 the clamp has made a one-half revolution, carrying the bars 13 from engaging position with the roller 38 to engaging position with the roller 39, said roller 39 through its engagement with the bars 13 will impart a 55 further slight additional longitudinal movement to said bars 13, permitting the pawls 19 to release themselves by gravity from the ends of the bars 13, as shown in Fig. 1. When said bars 13 have moved to engaging 60 position with the roller 42, such engagement 65

will move the bars 13 in an opposite direction longitudinally of the clamp, to a position which will again permit the strand wires to enter the slots or recesses 24 and 28 in the bars 13 and 12 respectively. This 70 operation is continued during the weaving of the fence fabric and until a roll of fence is completed, and by reason of the gripping action of the bars 13 and 12 upon the strand wires, said strand wires will be crimped to 75 provide for expansion and contraction of the wires during heat and cold, as is well understood.

It is observed that various changes may be made in the construction and method of 80 operation of the clamp without departing from the spirit and scope of the invention, and I therefore do not wish to be limited to the details of construction shown.

What I claim is:—

1. In a clamp, in combination, a plurality of clamping and crimping bars, one of which is adapted to be moved longitudinally of the other, and a pivotally supported member adapted to engage with an end of said movable bar to lock it in crimping position.

2. In a clamp, in combination, a plurality of clamping and crimping bars, one of which is adapted to be moved longitudinally of the others, means adapted to engage said movable bar to move it to crimping position, a pivotally supported member adapted to engage with an end of said movable bar to lock it in crimping position, means to impart slight additional movement to 100 said movable bar after the crimping operation to permit said locking member to release itself by gravity, and means to move said movable bar to inoperative position.

3. In a clamp, in combination, a rotatable 105 support, a plurality of clamping and crimping bars mounted on said support, one of which is adapted to be moved longitudinally of said support, a roller at one end of said support adapted to engage and reciprocate 110 said movable bar, a member pivotally mounted on said support adapted by gravity to engage with the end of said movable bar to lock it in crimping position, a roller at the corresponding end of said support as said 115 first-mentioned roller to impart slight additional movement to said movable bar after the crimping operation to permit said locking member to release itself by gravity, and a roller at the opposite end of said support 120 to move said movable bar to inoperative position.

4. In a clamp, in combination, a rotatable support, a plurality of sets of clamping and crimping bars mounted on said support, each 125 set of bars including three bars, the center bar of each set adapted to be reciprocated while the remaining bars of each set are immovable, diametrically disposed rollers at one end of said support, one of said rollers 130

- adapted to engage each reciprocal bar to move it to clamping and crimping position, a locking member having a pivotal connection with each pair of immovable bars and 5 adapted to lock said reciprocal bars in crimping position when moved by said first-mentioned roller, the other of said rollers adapted to engage and impart slight additional reciprocal movement to said movable 10 bars to permit said locking members to release themselves by gravity from said movable bars, and a roller mounted at the opposite end of said support, adapted to engage with said reciprocal bars after the operation of 15 said second-mentioned rollers, to move said reciprocal bars to inoperative position.
5. In a clamp, in combination, a shaft, heads mounted thereon to rotate therewith, a plurality of sets of clamping and crimping 20 bars, each set of bars including one bar which is adapted to be reciprocated on said heads, locking means associated with each set of bars adapted to engage with and lock said reciprocal bars in crimping position, diametrically disposed rollers at one end of 25 said clamp, one adapted to move said reciprocal bars to crimping position, the other of said rollers adapted to engage with and impart slight additional movement to said reciprocal bars to permit the release of said locking means, and a roller at the opposite end of said clamp adapted to engage with and move said reciprocal bars in an opposite direction and into inoperative position. 30
6. In a clamp, in combination, a shaft, heads mounted thereon to rotate therewith, a plurality of sets of clamping and crimping bars, each set of bars including one bar which is adapted to be reciprocated on said heads, 35 locking means associated with each set of bars adapted to engage with and lock said reciprocal bars in crimping position, diametrically disposed rollers at one end of said clamp, one adapted to move said reciprocal bars to crimping position, the other of said rollers adapted to engage with and impart slight additional movement to said reciprocal bars to permit the release of said locking means, a roller at the opposite 40 end of said clamp adapted to engage with and move said reciprocal bars in an opposite direction and into inoperative position, a support for said last-mentioned roller, and means for holding said roller in yielding engagement with said reciprocal bars. 45
7. In a clamp, in combination, a plurality of clamping and crimping bars, the outside bars having fixed positions and the center bar adapted to be reciprocated therebetween, 50 said center bar having a cut-out portion at one end, a pawl pivoted between said fixed bars and operable in said cut-out portion of said center bar and adapted to have engagement with the end of said center bar to lock the same in crimping position, means 55 to move said center bar to crimping position, and other means to move said center bar to permit said pawl to release itself from said center bar by gravity. 60
8. In a clamp, in combination, a plurality of clamping and crimping bars, the outside bars having fixed positions and the center bar adapted to be reciprocated therebetween, said center bar having a cut-out portion at one end, a pawl pivoted between said fixed bars and operable in said cut-out portion of said center bar and adapted to have engagement with the end of said center bar to lock the same in crimping position, means 65 to move said center bar to crimping position, other means to move said center bar to permit said pawl to release itself from said center bar by gravity, said fixed and said center bars each having recessed portions which are adapted to coincide and to receive 70 strand wires, and bearing pins in the walls of the recesses of said bars. 75
9. In a clamp, in combination, a plurality of clamping and crimping bars, the outside bars having fixed positions and the center bar adapted to be reciprocated therebetween, said center bar having a cut-out portion at one end, a pawl pivoted between said fixed bars and operable in said cut-out portion of said center bar and adapted to have 80 engagement with the end of said center bar to lock the same in crimping position, a roller adapted to bear against one end of said center bar to move it to crimping position, a second roller adapted to bear against the corresponding end of said center bar as said first-mentioned roller to give additional slight movement to said center bar to permit said pawl to release itself by gravity from said center bar, and a third roller to 85 impart reverse movement to said center bar to move it to an inoperative position, and a yielding support for said last-mentioned roller. 90
10. In a clamp, in combination, a plurality of clamping and crimping bars, the outside bars having fixed positions and the center bar adapted to be reciprocated therebetween, each of said bars provided with cut-out portions adapted to coincide, replaceable bearing pins in corresponding walls of the recesses of said fixed bars, a replaceable bearing pin in the wall of said recesses of said center bar, opposite said pins in said fixed bar, whereby they may 100 engage and crimp a wire therebetween, means to reciprocate said center bar, means to engage one end of said center bar to lock it in crimping position, and means to move said center bar to release said locking means. 105
11. In a clamp, in combination, a revolvable support, clamping and crimping bars on said support, certain of said bars adapted 110

to be reciprocated, means to move said reciprocal bars to crimping position, means to lock said reciprocal bars after being moved to crimping position, other means to impart additional movement to said reciprocal bars to release said locking means, means to impart reverse movement to said reciprocal bars to move the same to inoperative position, a support for said reversing means, yielding securing means for said support, 10 and means to yieldingly hold said reversing means against said reciprocal bars.
